(Cl. D44—29)

To all whom it may concern:

Be it known that we, James L. Hvale and Robert A. Murray, both citizens of the United States, residing at Chicago and Evanston, respectively, in the county of Cook and State of Illinois, have invented a new, original, and ornamental Design for a Handle for a Knife, Kitchen Utensil, or Similar Article, of which the following is a specification, reference being had to the accompanying drawing, forming part thereof.

Fig. 1 is a plan view of a handle for a knife, kitchen utensil, or similar article, showing our new design.

Fig. 2 is a side view of the same.

Fig. 3 is an end view illustrating the article when viewed from the left of Fig. 2.

Fig. 4 is an end view of the article as it appears when viewed from the right of Fig. 2.

We claim:

The ornamental design for a handle for a knife, kitchen utensil, or similar article, as shown.

JAMES L. HVALE.
ROBERT A. MURRAY.
